UNITED STATES PATENT OFFICE.

WILLIAM C. ANTHONY, OF STREATOR, ILLINOIS.

OIL BURNER.

Application filed December 17, 1925. Serial No. 75,926.

This invention relates to a burner, and particularly to a burner adapted to prepare for burning and burn liquid fuel. It has for one object to provide means for driving the feeding and mixing apparatus. It has for another object to provide such a driving means which is free from mechanical linkage and in which all mechanically engaged parts are outside of any heated zone. Other objects 5 will appear from time to time throughout the specification and claims.

My invention is illustrated more or less diagrammatically in the accompanying drawing, wherein:

15 Figure 1 is a vertical cross section with parts in elevation showing the burner and drive and associated parts in position in the heating chamber;

20 Figure 2 is a vertical cross section on an enlarged scale showing the mixing or vibrating and feeding member with the drive parts.

Figure 3 is a horizontal cross section taken on line 3—3 of Figure 2;

25 Figure 4 is a cross section taken on line 4—4 of Figure 2;

Figure 5 is a detailed cross section on an enlarged scale taken on line 5—5 of Figure 2.

Like parts are designated by like characters throughout.

30 A is a boiler having a base portion A¹ supported on any suitable floor or foundation A². It is provided with a combustion chamber A³.

B is a pilot light supplied preferably with a gas pipe B¹ which is controlled by a valve 35 B². C is a vaporizer assembly. It is formed of a hollow generally tubular housing C¹ which is connected to an impeller housing C² which has a removable bottom C³ in which is formed a cup-like oil retaining pocket C⁴.

40 Mounted within the member C² is a rotating shaft D provided with an upwardly flaring central bore D¹ and a laterally enlarged bottom portion D², which is provided with a plurality of pick-up channels D³ which communicate with the bore D¹ at or near its bottom.

45 At its top the member D is threaded and has seated upon it a cap E which is provided with lateral openings E¹.

F is an upwardly flaring mixing member 50 provided in its bottom with openings F¹ and having at its top a detachable cover F² which is provided with downwardly depending spacing elements or parts F³ which are seated in a ledge or groove F⁴ adjacent the top of the cup F. The cover F² is held in position by means of a bolt F⁵ which engages the cover

and the cap E. Suitable anti-friction bearings G G support the member D.

H is a nozzle formed or communicating with a supply pipe H¹. It is designed to discharge a jet of liquid against the blades I of the impeller turbine, which blades are joined to a hub I¹ which is fastened about the lower portion of the member D by means of a set screw I².

60 J is a discharge pipe adapted to receive liquid after it has been discharged against the impeller and dropped and fallen from it. J¹ is a valve in line with the discharge pipe J which pipe discharges into the overflow tank. 65

K is a fuel supply tank. K¹ is a supply connection controlled by a valve K² which is itself controlled by a float and lever assembly K³. These features form no particular part of the present invention and any type 70 of supply tank may be used.

75 L is a pump and in the form of the invention here shown a centrifugal pump is used. L¹ is an electric motor adapted to drive the pump. L² is a supply connection communicating with the tank K by means of which liquid is drawn from the tank to the pump and discharged into the supply pipe H¹ which communicates with the nozzle H. L³ is a relief pipe controlled by a safety valve L⁴. 80

85 M M are electric wires from any suitable power source by means of which electric power is supplied to the motor. M¹ is a thermostatic time controlled instrument adapted to control operation of the motor and through it the operation of the burner. These features form no particular part of the present invention, and any form of such devices might be used without departing from the spirit of the invention.

90 95 The use and operation of my invention are as follows:

The rotary assembly formed of the hollow member C and the cup F and the pick-up member D² is mounted in the heated zone. 100 When the furnace is in operation they are heated, but are to some degree cooled because a blast of air is carried inwardly through the cup and into the burning chamber. When the burner is not in operation, 105 the blast of air is discontinued or its strength greatly reduced and the heat formed in the combustion chamber of the boiler or furnace passes outward and to some degree heats the entire rotary assembly. For this reason it 110 is desirable to have the parts so constructed that the action of heat upon them is as nearly

negligible as possible. For this reason the device shown embodies no mechanical linkage. Any expansion of the parts or the activating fluid, therefore does not interfere with the 5 operation of the device because with the exception of the anti-friction bearings, no accurate fits are necessary and in the drive proper there is no metallic contact between driving and driven members.

10 When it is desired to operate the burner, the motor is turned on and it operates the pump which draws fuel from the tank and forces it through the supply system to the nozzle. It is driven under great pressure and 15 at very high speed against the impulse turbine and thus rotates it at high speed. This, of course, rotates the supply and mixing devices D and F.

10 After the impelled liquid has struck the 20 blades of the turbine, it falls downward and most of it passes out through the discharge connection. Some is always caught within the pocket C⁴ and is picked up by the pick-up elements D² and brought into the bore D¹, whence it passes upward along this bore 25 under the influence of centrifugal force. After leaving the bore it is thrown into the inside of the cup F, passes up along it and is mixed with and drawn into the openings 30 F¹ and the combustible mixture of air and fuel passes out between the upper edge of the cup F and the top F² and is ignited by the pilot light B and thereafter is burned. To some degree fuel is taken in directly through 35 the bottom of the bore D which is preferably open and passes upward as above described under the influence of centrifugal force. The pick-up openings D³ are provided to assist in picking up the necessary fuel and bring it to 40 the bore D¹ where it can be acted upon by centrifugal force.

I claim:

1. In combination in a furnace, a moving fuel preparing element including a generally 45 tubular member, carrying an impeller part, shaped to engage a liquid projected against it, a fuel pick up member mounted on the bottom of such tubular member in communication with the interior thereof, and an air 50 and fuel mixing and preparing member such member provided with perforations adapted to admit air, and means for supplying fuel under pressure to such moving element, to cause the same to rotate such fuel pick-up member 55 adapted to pick up fuel and force the same to the interior of such tubular member and from which the fuel is forced by centrifugal action to the mixing member.

2. In combination in a furnace, a rotary 60 fuel preparing element including a generally tubular member, a fuel pick-up member mounted on the bottom of such tubular member, and an air and fuel mixing and preparing member, such preparing member provided 65 with perforations through which air is drawn

in, and a turbine wheel fixed upon said tubular member, and means for supplying fuel under pressure against such turbine wheel whereby the same is caused to rotate such fuel pick-up member adapted to pick up fuel and 70 force the same to the interior of such tubular member and from which the fuel is forced by centrifugal action to the mixing member.

3. In combination in a furnace a rotary fuel preparing element including a generally 75 tubular member, a fuel pick-up member mounted on the bottom of such tubular member in communication with the interior thereof, and an air and fuel mixing and preparing member at the upper end of such tubular member 80 provided with perforations through which air is drawn in, and a turbine wheel fixed upon said tubular member, and means for projecting fuel under pressure against such turbine wheel, comprising a nozzle 85 adapted to project the fuel violently against the turbine whereby the same is caused to rotate such fuel pick-up member adapted to pick up fuel and force the same to the interior of such tubular member and from which 90 the fuel is forced by centrifugal action to the mixing member.

4. In combination in a furnace, a rotary fuel preparing element including a generally 95 tubular member, provided with an upwardly flaring inner cavity, a fuel pick-up member at the bottom of such tubular member in communication with the interior thereof, and an air and fuel mixing and preparing member at the upper end of such tubular member 100 such member provided with perforations adapted to admit air, and a turbine wheel fixed upon said tubular member, and means for supplying fuel under pressure against such turbine wheel whereby the same is 105 caused to rotate such fuel pick-up member adapted to pick up fuel and force the same to the interior of such tubular member and from which the fuel is forced by centrifugal action to the mixing member.

5. In combination in a furnace, a rotary fuel preparing element including a generally 110 tubular member provided with an upwardly flaring inner cavity, a fuel pick-up member at the bottom of such tubular member 115 in communication with the interior thereof and provided with channels communicating with such interior cavity and an air and fuel mixing and preparing member at the upper end of such tubular member such member provided with perforations adapted to admit air, and a turbine wheel fixed upon said tubular member, and means for supplying fuel under pressure against such turbine 120 wheel, such means including a pressure creating apparatus, a conduit system, and a nozzle adapted to project the fuel violently against the turbine whereby the same is caused to rotate such fuel pick-up member 125 adapted to pick up fuel and force the same 130

to the interior of such tubular member and from which the fuel is forced by centrifugal action to the mixing member.

6. In combination, an apparatus for burning fuel and preparing the same for combustion, a rotary fuel preparing means including a perforated member, a mixing member carried by such perforated member and mounted to move with it the two being in communication with each other and a turbine wheel located on such perforated member, a housing for such turbine wheel within which it is located and a pick-up member within such housing mounted on such perforated member and means for supplying fuel under pressure to such turbine wheel to rotate the same, such pick-up member being adapted to pick up a certain portion of the fuel after the same has passed from the turbine wheel to conduct such fuel to the interior of such perforated member.

7. In combination, an apparatus for burning fuel and preparing the same for combustion, a rotary fuel preparing means including

a perforated member, a mixing member carried by such perforated member and mounted to move with it the two being in communication with each other and a turbine wheel located on such perforated member, a housing for such turbine wheel within which it is located and a pick-up member within such housing mounted on such perforated member and means for supplying fuel under pressure to such turbine wheel to rotate the same, such pick-up member being adapted to pick up a certain portion of the fuel after the same has passed from the turbine wheel to conduct such fuel to the interior of such perforated member, there being a reservoir cavity within such turbine housing adapted to receive and retain a portion of the fuel after the same passes from the turbine wheel, such pick-up member being located within such cavity.

Signed at Chicago, county of Cook and State of Illinois, this 15th day of December, 1925.

WILLIAM C. ANTHONY.
